UNITED STATES PATENT OFFICE.

WALTER C. WESTAWAY, OF ROCKFORD, ILLINOIS, ASSIGNOR OF ONE-HALF TO THOMAS DUNN, JR., OF ROCKFORD, ILLINOIS.

CARBURETER.

No. 909,490.

Specification of Letters Patent.

Patented Jan. 12, 1909.

Application filed October 25, 1905. Serial No. 284,391.

To all whom it may concern:

Be it known that I, WALTER C. WESTAWAY, a citizen of the United States, residing at Rockford, county of Winnebago, and 5 State of Illinois, have invented certain new and useful Improvements in Carbureters, of which the following is a description.

My invention belongs to the general class of devices designed to thoroughly commingle 10 air and a suitable liquid, such for example as a hydro-carbon, for any desired purpose, and has for its object the production of simple and effective means for the purpose.

To this end my invention consists in the 15 novel construction, arrangement and combination of parts herein shown and described and more particularly pointed out in the claims.

In the drawings wherein like reference 20 characters indicate like or corresponding parts, Figure 1 is a vertical sectional view showing my improved carbureter, Fig. 2 is a bottom plan of the same, Fig. 3 is a plan view of the valve seat, dotted lines indicating the 25 relative position of the conducting groove in the valve connected therewith, Fig. 4 is a plan view of the valve, Fig. 5 is a view of a modified form of cam member, Fig. 6 is a bottom plan of the same, and Fig. 7 is another 30 form of adjustable cam.

In the preferred form shown in the drawings, 1 represents a suitable base and 2 a top for a shell or casing forming a mixing chamber. The two may be secured together in 35 any preferred manner. As shown lugs 3—3 formed upon the two parts and registering with one another serve as seats for suitable clamping bolts (not shown) which firmly secure the two parts together. The base is 40 preferably formed with a circular opening into which fits a bottom piece 4 which is slightly smaller than the opening in the base forming an annular inlet 5 between the two for the liquid. The bottom piece 4 is secured in position by suitable bolts 6—6 or equivalent means. An opening 7 is formed 45 in the bottom piece 4 which serves as an air inlet while 8 serves as an outlet for the shell. An offset or extension 9 has formed thereon a 50 valve seat 10 provided with a duct 11 and extending from the liquid supply pipe 12 to the seat and a second duct 13 extending from the valve seat to the inlet 5. A valve stem 14 extends through the valve seat and carries a valve 15 and a cam 16 a spring 17 or equiva-

lent means being positioned between the two to resiliently maintain the valve in contact with its seat, the same being snugly positioned within a recess formed within the extension for that purpose. A valve 18 arranged to cover the air inlet 7 is preferably hinged to the bottom piece 4 and 19 and is provided with an arm 20 extended in the path of the cam 16. A support 21 carried by the bottom 4 supplies a seat for a spring 22 positioned between the support and the valve 18, serving as resilient means to normally hold the valve closed. The valve stem 14 is supported in a suitable bearing 23 carried by the top 2, and a handle 24 serves as means for operating said valve stem.

The mode of operation as thus described is as follows: Normally the solid portion of the valve 15 covers the port 11 and prevents the passage of liquid into the mixer. Upon rotating the valve stem 14 the groove 25 registers with the ducts 11 and 13 and permits the fluid to pass from the supply pipe 12 to the inlet 5. By the same movement the cam 16 operates the lever 20 overcoming the spring 22 and partially uncovering the air inlet 7. It will be obvious that the extent to which either of the valves is opened depends upon the rotation of the valve stem 14 and that the two inlets are opened synchronously and to a pre-determined extent relatively to one another. The groove 25 in the valve 15 is eccentrically formed to the axis of rotation and is gradually increased both laterally and in its depth from the beginning to the larger end. For convenience it may be termed an increasing spiral groove. As the groove first registers with the inlet 11 it cuts by the opening permitting a small quantity of the fluid to enter and be gradually conducted to the duct 13. As the valve is further rotated the groove further uncovers the inlet 11 bringing the larger and deeper portions of the groove into complete registry therewith permitting larger quantities of the fluid to enter. This requires the rotation of the inlet valve and by this rotation the air valve is correspondingly opened so that as the liquid is increased so also is the air. In the preferred construction a small duct 26 is formed in the air valve 18 permitting the escape of any accumulated fluid when the device is not in operation and at the same time permitting a small quantity of air to enter and mingle with any accumulated fluid so that a small 110

quantity of the carbureted air is retained in the device which may be utilized in starting up the operation.

5 A collar 27 carried by the valve stem 14 and resting upon the extension 9 prevents the accidental disengagement of the valve 15 from its seat.

The cam 16 is preferably adjustable so that the extent to which the air valve will be 10 operated may be regulated as desired. This may be accomplished either by releasing the set-screws 28 and rotating the cam member 16 around upon the valve stem to bring the higher part of the cam earlier into action with 15 the arm 20 when by again setting the set-screw the parts may be firmly connected, or it may be done by providing means for regulating the inclination of the cam surface. This result may be secured in any desired manner, 20 one simple means being shown in the drawings. In Figs. 5 and 6 the cam member comprises a plate 29 provided with a series of bolts or screws 30 the ends of which project to form the cam surface. By adjusting 25 the screws or bolts 30 as desired the inclination and height of the cam may be regulated as desired.

In the preferred construction a spreader 31 is positioned within the mixer and normally serves to substantially close the liquid inlet 5 as well as the air inlet 7. Guiding means carried by the spreader serves to direct it in its operation. These consist in a stem 32 loosely positioned in a seat carried 35 by a plate 33 and in lugs 34 loosely positioned in the air inlet. A spring 35 serves to resiliently maintain the spreader in its normal position the operation being insured by the action of the engine or a co-operating pump 40 connected therewith. This will give a pulsating action the spreader being periodically lifted from its seat permitting the inflow of the regulated quantities of fluid and air and upon returning to its seat will contact with 45 the inflowing liquid and spread the same out into a film between the proximate parts over which the inflowing current of air is directed at the next movement. Baffle plates 36 may be employed if desired, to insure a more 50 perfect mixture of the inflowing air and liquid. The supporting plate 33 may serve as one of the series of baffle plates.

Having thus described my invention, what I claim as new, and desire to secure by Letters Patent is:—

1. A carbureter comprising a shell or casting provided with a liquid inlet, an air inlet, and an outlet, in combination with a valve hinged in proximity to the air inlet and normally closing the same, a valve for the liquid inlet a cam member operated by the liquid valve, and intermediate mechanism between the air valve and the cam member whereby upon operating the liquid valve the air valve 65 will be synchronously operated.

2. A carbureter comprising a shell or casting provided with a liquid inlet, an air inlet, and an outlet, in combination with a valve supported in proximity to the air inlet and resilient means for normally holding the said valve closed, a valve for the liquid inlet, a cam member connected to the liquid valve, and intermediate mechanism between the air valve and the cam member for controlling the operation of said air valve by the movements of said cam.

3. A carbureter comprising a shell or casting provided with a liquid inlet an air inlet and an outlet, in combination with a valve supported in proximity to the air inlet, resilient means for normally maintaining the said valve in a closed position, an arm carried by said valve extending outward therefrom, a valve for the liquid inlet, and a cam member connected to the liquid valve and 85 co-operating with the extending arm of the air valve for controlling the operation of said air valve by the movements of said cam.

4. A carbureter comprising a shell or casting provided with a liquid inlet, an air inlet, and an outlet, in combination with a valve for the liquid inlet, an adjustable cam member operated by the liquid valve and a valve supported in proximity to the air inlet provided with resilient means for normally maintaining said valve in a closed position, 95 said air valve being provided with an arm extending in the path of the cam, whereby the operation of the liquid valve will also operate the air valve.

5. A carbureter comprising a shell or casting provided with a liquid inlet, an air inlet, and an outlet, in combination with a valve supported in proximity to the air inlet and normally closing the same, an aperture 26 10. formed in said valve, a valve for the liquid inlet, a cam member operated by the liquid valve, and intermediate mechanism between the air valve and the cam member, whereby the operation of the liquid valve will operate 110 the air valve.

6. A carbureter comprising a shell or casting provided with a liquid inlet, an air inlet, and an outlet, in combination with a rotatable valve for the liquid inlet, an adjustable 115 cam member carried by the liquid valve, and a valve supported in proximity to the air inlet and normally closing the same, provided with an arm extending into the path of said cam member, whereby the operation of said air valve is controlled by the movements of said liquid valve.

7. A carbureter comprising a shell or casting provided with a liquid inlet, an air inlet and an outlet, in combination with a rotatable 125 valve for the liquid inlet, a cam member carried by said valve, an air valve covering the air inlet and resiliently maintained in a position to normally close the same, and intermediate mechanism between the air valve

and the cam member, for controlling the operation of said air valve by the movements of said cam.

8. A carbureter comprising a shell or casing provided with an annular liquid inlet, an air inlet and an outlet, in combination with a rotatable valve for the liquid inlet, a cam member operated by the liquid valve, a resilient air valve normally closing the air inlet, 10 and intermediate mechanism between the air valve and the cam member, whereby the operation of the liquid valve will also operate the air valve.

9. A carbureter comprising a shell or casing provided with an annular liquid inlet, an air inlet and an outlet, in combination with a valve for the liquid inlet a cam member operated by the liquid valve, an air valve normally closing the air inlet, and provided with 20 an arm extending in the path of the cam member, and a spreader arranged within the shell and normally tending to spread the inflowing liquid into a film.

10. A carbureter comprising a shell or casing provided with an annular liquid inlet, an air inlet and an outlet, in combination with a rotatable valve arranged to regulate the inflow of the liquid, an adjustable cam member operated by the valve, an air valve normally closing the air inlet and resiliently maintained in such position, means for transmitting the operation of the cam to the air valve, and a movable deflector within the shell tending to normally close the liquid inlet and the air inlet.

11. A carbureter comprising a casing provided with a liquid inlet, an air inlet, and an outlet, in combination with a valve upon the exterior of said casing for each of said inlets, 40 and intermediate mechanism between said

valves whereby upon operating the liquid valve the air valve will be synchronously operated.

12. A carbureter comprising a casing provided with a liquid inlet, an air inlet, and an outlet, in combination with a rotatable valve upon the exterior of said casing for said liquid inlet, and a hinged valve upon the exterior of said casing for said air inlet, and intermediate mechanism between said valves whereby upon operating the liquid valve the air valve will be synchronously operated. 45

13. A carbureter comprising a casing provided with a liquid inlet, an air inlet, and an outlet, in combination with a valve upon the exterior of said casing for each of said inlets, intermediate mechanism between said valves whereby the operation of the liquid valve will synchronously operate the air valve, and a deflector positioned within the casing arranged to spread the inflowing liquid into a film. 55

14. A carbureter comprising a casing provided with a liquid inlet, an air inlet, and an outlet, in combination with a valve upon the exterior of said casing for each of said inlets, intermediate mechanism between said valves whereby the operation of the liquid valve will synchronously operate the air valve, and a resiliently actuated movable deflector positioned within the casing arranged to spread the inflowing liquid into a film and normally close both of said inlets. 65

In testimony whereof, I have hereunto signed my name in the presence of two subscribing witnesses. 75
